UNITED STATES PATENT OFFICE.

CHARLES GRAFF, OF NEW YORK, N. Y.

DESIGN FOR A BACK FOR BRUSHES, &c.

SPECIFICATION forming part of Design No. 23,151, dated March 27, 1894.

Application filed December 26, 1893. Serial No. 494,817. Term of patent 7 years.

To all whom it may concern:

Be it known that I, CHARLES GRAFF, a citizen of the United States, residing in the city, county, and State of New York, have invented 5 and produced a new and useful Design for the Backs of Brushes, Hand - Mirrors, and Similar Articles, of which the following is a specification, reference being had to the accompanying drawing, forming a part thereof, o said drawing illustrating my novel design applied to the back of a brush.

The leading feature of my design consists in an ornamental border of flower, scroll and shell work, leaving a plain center, the ornamentation in flower scroll and shell work ex-

tending down the handle of the article. The conventional scroll and shell work *a*, repeated at intervals, is interspersed with flower work *b* and patterns *c*, plain spaces *d* being left within the scroll and shell work, and the oval 20 center inclosed by the border being left plain.

What I claim is—

The design for the backs of brushes and similar articles, substantially as shown and described.

CHARLES GRAFF.
